UNITED STATES PATENT OFFICE.

GEORGE R. CORNWALL, OF RYE, NEW YORK.

APPARATUS FOR APPLYING INK TO THE SURFACE OF A PRINTING-PLATE.

1,181,645.

Specification of Letters Patent.

Patented May 2, 1916.

Application filed June 15, 1910, Serial No. 567,053. Renewed October 7, 1915. Serial No. 54,692.

To all whom it may concern:

Be it known that I, GEORGE R. CORNWALL, a citizen of the United States, and a resident of Rye, in the county of Westchester and State of New York, have invented certain new and useful Improvements in Apparatus for Applying Ink to the Surface of a Printing-Plate, of which the following is a specification.

10 This invention relates to devices for strengthening designs on planographic printing plates.

Objects of the invention are to provide for a uniform distribution of the ink preparatory to applying it to the plate; to secure a uniform distribution of the ink over the surface of the printing plate; to provide for a careful and thorough working in of the ink into the design; to effect 20 these objects rapidly and with a minimum of time and of skill and exertion on the part of the operator; to provide novel and effective power driven ink applying means, and to provide power driven means for the 25 initial distributing of the ink and also for applying the ink to the surface of the printing plate. These and other objects of invention will in part be obvious and will in part more fully appear herein.

30 The invention consists in the novel parts, articles, arrangements, combinations and improvements herein shown and described.

The accompanying drawings, referred to herein and forming a part hereof, illustrate one embodiment of the invention, the same serving in connection with the description herein to explain the principles of the invention.

Of the drawings:—Figure 1 is a view partly in perspective of the ink distributing table, a plate support, the ink supplying means and the guide therefor and shows the device being used to distribute and collect the ink and also being used to apply the 45 ink to the surface of the printing plate; Fig. 2 is a view of the ink applying pad and the handle attached thereto; Fig. 3 is a fragmentary view, partly in section, corresponding to the lower part of Fig. 2; Fig. 4 shows the connection between the driving 50 motor and the ink applying means; Fig. 5 is a side elevation looking at Fig. 4 from the right; and Fig. 6 is a top plan of the lower part of Fig. 4 from the joint in the 55 casing.

Referring to the accompanying drawings

illustrating by way of example one embodiment of the invention, a support or table 1 is shown carrying thereon an ink slab 2. Contiguous thereto is shown a support 3 for 60 the printing plate 4.

The ink applying means shown herein comprises a pad-head or support 10, having a shank 11, passing through the handle or hand piece 12, and being mounted to freely 65 rotate within the hand piece 12, and connecting to the flexible shaft 13. The head 10 may be of metal or other rigid substance, and may be of circular form and may also have its operating face convexly curved. 70 Upon the operating face of the head 10 is shown a resilient pad 14 of felt or other suitable material which may be attached to the head 10 in any suitable way, as by an adhesive, or by stitches 15 passing through 75 the layer 14 and through apertures in the head 10. An outer covering 16, constituting the ink applying surface of the pad, of chamois, or other suitable material, may be folded about the head 10 and the layer 14 80 and may then be gathered together at the center of the back surface of the head 10. A knurled clamping nut 17 is shown threaded on the threaded exterior of the shank 11 (see Fig. 3) and may be screwed 85 down upon the gathered in ends of the covering 16, as shown in Fig. 2, to hold it firmly in position.

The flexible shaft 13 is given a rotatory motion by suitable means, the form thereof 90 herein shown comprising a short shaft 20 journaled in a casing 21. The shaft 20 is shown horizontally arranged, and projecting from the inclosed casing 21 and being coupled at one end 22 to the shaft 13. 95 Mounted upon the shaft 20, to rotate therewith is shown a worm wheel 23 and mounted above the shaft 20 in the casing 21 is shown a worm 24 carried upon a shaft 25 of an electric motor 26.

The casing 21 is shown divided horizontally into two parts, an upper part 30 and a lower part 31, dividing the casing horizontally through the journals 32 and 33 of the shaft 20. The two parts of the casing 21 105 may be held together in a suitable manner, as by the clamping screws 34 and 35. The casing 21 is thus completely closed, and the shaft 20 and worm wheel 23 may be run in an oil bath, which through the movement 110 and contact of the parts will also serve to keep the worm 24 and its shaft thoroughly

lubricated. This will serve to keep the parts cool, and to cause them to run easily at a high speed. The lower part of the casing 31 is shown formed into a pedestal 36.

The motor and its driving mechanism are shown suitably mounted contiguous to the ink slab and to the plate support so that the rotating ink pad may be passed readily from one to the other in the work of distributing the ink upon the slab, transferring it to the plate, and applying it upon and working it into the surface of the printing plate. In the present embodiment 15 the motor 26 and the casing 21, and their associated parts are shown mounted in the pan 40 which serves to catch all drippings, the pan 40 being placed upon a support 41 carried by hangers 42 and 43. A suitable 20 hook 44 is shown for hanging up the inking pad when not in use.

In using the invention, the handle 12 is grasped by the hand of the operator, the motor at the same time rotating the flexible 25 sheet 13 and the inking pad therewith. The inking pad may be passed by movement of translation across the surface of the ink distributing slab 2, the inking pad at the same time having its own rotatory motion 30 about its own axis, as just described. When the ink has been taken up by the surface of the inking pad, said pad may be moved by the operator over to the printing plate 4, as shown in dotted lines in Fig. 1 and 35 the pad then be rapidly moved over the face of the printing plate in a movement of translation by the hand of the operator, the pad at the same time having its rotatory motion about its own shaft.

40 It will be understood that the inking pad has a movement entirely different from that of the inking pad as ordinarily used in the hands of the operator. Also in the case of this invention, the operator may give his 45 attention entirely to the degree of pressure or contact which he desires to exercise upon the surface of the printing plate, and to moving the pad to and fro across the surface of the plate, or moving it from one 50 point to another on the plate as may be found desirable or necessary. During all this time the pad has the rotatory motion about its own axis, causing a fine and uniform deposition of the ink from the face 55 of the pad upon the plate. This conduces to nice and exact work both through the peculiar movement of the pad, and through the fact that the operator may devote his 60 entire attention to position the pad both to get the right contact with the plate and to locate the action upon the desired part of the plate.

65 It will be understood that certain changes may be made from the structure shown and described, within the scope of the accom-

panying claims, and without departing from the principles of the invention.

What I claim as my invention and desire to secure by Letters Patent, is:

1. An apparatus for applying ink to the surface of a printing plate including in combination an inking pad having a head and an ink-taking and an ink-imparting member detachably carried over the operating face of said head, and means for holding said member taut or firmly in position over the operating face of said head; means for giving a continuous rotatory motion to the said pad, and means whereby the said pad may be moved by the hand of the operator over the surface of the plate, and the degree of pressure between the inking pad and the plate regulated at the same time.

2. An apparatus for applying ink to the surface of a printing plate including in combination an inking pad having a head and an ink-taking and an ink-imparting member detachably carried over the operating face of said head and means for holding said member taut or firmly in position over the operating face of said head; means for giving a continuous rotatory motion to the said pad, about its own axis, and means whereby the said pad may be moved by the hand of the operator over the surface of the plate, and the degree of pressure between the inking pad and the plate regulated at the same time.

3. An apparatus for applying ink to the surface of a printing plate including in combination an ink distributing slab, a printing plate located contiguously to said ink distributing slab; an ink applying pad; means for continuously rotating said ink applying pad; and means whereby the rotating ink applying pad may be moved by hand to and fro between the ink slab and the printing plate to take ink from the ink slab and apply it to the printing plate while so rotating.

4. An apparatus for applying ink to the surface of a printing plate including in combination an ink distributing slab, a printing plate supported contiguous thereto, an ink applying pad, a flexible shaft connected thereto to impart a rotatory motion thereto, a non-rotating hand piece adjacent to said ink pad, and means for rotating said flexible shaft, whereby the rotating ink pad may be moved to and fro between the ink distributing slab and the surface of the printing plate.

5. An apparatus for applying ink to the surface of a printing plate including in combination an ink distributing slab, a printing plate located contiguously to said ink distributing slab; an ink applying pad; means for rotating said ink applying pad; and means whereby the ink applying pad may be moved to and fro between the ink slab

and the printing plate to take ink from the ink slab and apply it to the printing plate while so rotating.

6. An apparatus for applying ink to the surface of a printing plate including in combination an ink distributing slab, a printing plate contiguous thereto, a pad having an ink taking and ink applying surface and rotating about its own axis, rotating means for said pad and connections between said pad and rotating means whereby said pad while rotating may be moved to and fro by the hand of an operator between the ink

slab and printing plate to receive a supply of ink from the slab and apply it to the 15 plate and the degree of pressure and location of application of said rotating ink pad upon the plate may be accurately controlled.

In testimony whereof, I have signed my name to this specification, in the presence of 20 two subscribing witnesses.

GEORGE R. CORNWALL.
